UNITED STATES PATENT OFFICE.

JOHN H. CROWELL, OF PROVIDENCE, RHODE ISLAND.

SEPARABLE BUTTON.

SPECIFICATION forming part of Letters Patent No. 228,984, dated June 22, 1880.

Application filed March 8, 1880. (Model.)

To all whom it may concern:

Be it known that I, JOHN H. CROWELL, of Providence, Rhode Island, have invented a new and useful Separable Button, of which 5 the following is a specification.

My invention relates to improvements in separable buttons in which the hollow post is engaged by a locking device operated by pushers; and the object of my improvement is to 10 construct in one piece the pushers, catches, and spring, and to retain said piece in a slotted post and the top of the button by means of a single-piece shoe. I attain these objects by mechanism illustrated in the accompanying drawings, in which—

Figure 1 is a vertical section of the entire button, and Fig. 2 a vertical section of the slotted post and shoe at right angles to the view of the post and shoe as shown in Fig. 1. 20 To the top A is secured the slotted post B. The pushers a a', catches b b', and spring C are constructed in one piece, which is placed into the slot of the post B and holes d d' in the sides of the top A, with the inside upper surface of the pushers bearing on the upper surface of the slot. The spring, pushers, and catches are then brought to a central position in the button and in the slot, where they are held by means of the concavity in the end 25 30 of the shoe D, which is secured to the post. While thus held the catches project equally

beyond the sides of the post, and when the two parts of the button are together they engage the inside of the shoulder formed on the end of the hollow post E, which is secured to 35 the bottom shoe, F.

Inside of the post E is secured the ring e, for holding the end of the post B steady when the two parts of the button are together.

To separate the two parts of the button the 40 pushers a a' are pressed together, thus contracting the spring c and pushing the catches b b' inside of the external diameter of the slotted post B and free from the shoulder on the end of the hollow post E, which permits the 45 top of the button, with its attached parts, to be separated from the bottom post, E, and bottom shoe, F.

What I claim as my invention, and desire to 50 secure by Letters Patent, is—

In a separable button, the combination of the top A, pushers a a', catches b b', spring c, slotted post B, and holding-shoe D with the hollow post E, having shoulders at its upper end, ring e at its lower end, and secured to the 55 shoe or bottom F, substantially as shown, for the purpose specified.

JOHN H. CROWELL.
